DUNCAN MCKENZIE, OF WINNIPEG, MANITOBA, CANADA.

SMOKE-PLUG.

1,137,344.

Specification of Letters Patent. Patented Apr. 27, 1915.

Application filed June 8, 1914. Serial No. 843,901.

To all whom it may concern:

Be it known that I, DUNCAN MCKENZIE, of the city of Winnipeg, in the Province of Manitoba, Canada, have invented certain new and useful Improvements in Smoke-Plugs, of which the following is the specification.

The invention relates to improvements in smoke plugs and the object of the invention 10 is to provide a plug which can be readily inserted within a pipe and easily expanded to close the pipe, a particular feature of the invention being that the ordinary Y-connection found in water systems can be closed 15 with the employment of a single plug instead of two plugs as is now commonly used.

A further object of the invention is to provide an effective plug having but few 20 parts and one which can be constructed at a reasonable price and requires but little skill in handling.

With the above objects in view the invention consists essentially in the arrangement and construction of parts hereinafter more 25 particularly described and later pointed out in the appended claims, reference being had to the accompanying drawing in which:

Figure 1 represents a vertical sectional view through the Y-connection with my plug 30 inserted. Fig. 2 represents a plan view of the under face plate. Fig. 3 represents a sectional view through the square pipe, the section being taken in the plane denoted by the line X—X' Fig. 1. Fig 4 is a face view of 35 the lower end of the shank showing the boss. Fig. 5 is a vertical sectional view centrally through the cup-shaped filler.

In the drawing like characters of reference indicate corresponding parts in each 40 figure.

1 represents the usual Y-connection as found in water installations which connection presents the usual branches 2 and 3. It is here remarked that in practice the upper 45 end of the Y-connection communicates with the usual drain pipe of a building while the lower end opens to the sewer pipe and the branch pipe 3 receives a screw plug which when removed allows of access to the interior of the Y-connection for testing and 50 cleaning purposes.

To understand the use of a smoke plug it is explained that after the water connections have been made in a building they are 55 subjected to what is termed a smoke and

water test. In order to carry this out it is necessary to close the connection to the sewer and this is always effected in the Y-connection, the smoke plug being inserted in the connection after the screw plug in the 60 branch 3 has been removed. In present practice two expansible members are usually used, one to close the branch pipe 3 and the other to close the lower end of the Y-connection leading to the sewer. 65

I wish here to point out that my plug is constructed so that only one expansible member is required, this being utilized to close the Y-connection above the branch 3. By designing my plug so that it can be inserted and expanded in the above location I am able to do away with the two expansible members as at present employed. Accordingly I am able to provide a very light, 70 serviceable and efficient plug as compared 75 with the more or less heavy complicated and costly plugs now customarily in use.

Referring again to the drawing: 4 represents a main shank having a centrally located vertically disposed square opening 5 80 therein and provided at the upper end with a circular face plate 6 and at the lower end with an offset boss 7 having a hollow interior which is continuous with the opening 5. The end of the boss has a coned face as 85 shown at 7', to provide a seat for the tapered inner end of a hollow square pipe 8 which has the outer end thereof rounded as shown. The face plate 6 is supplied with a projecting circular rib 6' for a purpose later explained. 90

9 is a roller located at the juncture of the boss with the shank and rotatably mounted on a cross pin 10.

11 is a circular upper face plate similar 95 to that 6, which face plate is supplied on the upper side with a permanent eye 12 and on the under side with a projecting guide spindle 13 slidably received within the square opening 5 of the shank. A circular 100 rib 14 projects also from the under side of the upper face plate, this rib being directly opposite the former rib.

15 is a rubber band inserted between the face plates and passing around the ribs. 105 This band is designed to be expanded upon the face plates being drawn together.

16 is an adjusting bolt having the outer end fitted with a nut 17 and a washer 18 and the inner end squared as shown at 19, the 110

squared inner end being designed to fit slidably within the open center of the pipe 8.

A flexible connection such as a cable 20 is secured to the squared end of the adjusting bolt and passes downwardly through the pipe, around the roller 9 and upwardly to the lower end of the spindle 13 to which it is permanently fastened.

The face plates and rubber band form 10 what I term an expansible member. This expansible member is arranged so that it can be inserted within the Y-connection through the branch pipe 3.

The plug is used in the following way: 15 To insert it one first removes the nut 17 and washer 18 to allow the pipe 8 to be withdrawn. The shank and expansible member are then inserted through the branch pipe 3, being forced up by the hand into the upper 20 branch 2 of the Y-connection. The pipe 8 is then replaced in the original position and the washer and nut are applied. The nut is screwed down on the bolt by the application of a wrench or other convenient tool and it 25 is here to be noticed that the square end 19 of the bolt 16 at this time serves to prevent the bolt from turning in the pipe and consequently avoids any twisting of the cable. As the nut is tightened up, the cable is 30 drawn taut with the result that the shank is drawn down and the band expanded. The complete plug in reality becomes a rigid structure owing to the tightening of the cable. The nut can be tightened to insure a 35 smoke and water tight joint between the plug and the pipe in which it is inserted. To remove the plug it is only necessary to undo the nut and withdraw the parts in the same manner as they were inserted.

40 I wish to call particular attention to the socketing, so to speak, of the inner end of the pipe 8 in the boss and the manner in which the joint here formed is tightened up or loosened depending on the tension brought on the cable. It is obvious that if the pipe were formed as an integral part of the shank it would be impossible to insert the plug in the pipe in the position shown. By socketing it as described this is rendered 45 possible and therein lies one of the chief features of my invention. The plug can be used with various sizes of pipes very readily. Where a large pipe is to be closed I provide a cup shaped rubber filler 21 with 50 a central opening 22 therein large enough to admit the shank. By placing this filler over the expansible member a large pipe can be plugged while still using my plug. I might remark that the filler mentioned 55 will be placed in position on the shank and around the expansible member when the pipe is removed. I mention this as, as far as I am aware, there is no other plug constructed in a manner which will allow a cup

shaped filler to be placed thereon to advantage. 65

What I claim as my invention is:

1. A smoke plug comprising an expansible member fitted with an extending shank, a pipe having one end demountably associated with the shank, a flexible member connected with the expansible member and passing normally through the shank and pipe and removable means for adjusting the tension in the flexible member to expand the 75 expansible member, said adjustable means being located at the free end of the pipe, as and for the purpose specified.

2. A smoke plug comprising an expansible member fitted with an extending shank, 80 a pipe disposed at an angle to the shank and having the inner end demountably associated with the shank, a cable connected to the expansible member and passing normally through the shank and pipe and 85 means located at the outer end of the pipe for adjusting the tension in the cable and thereby effecting the expansion of the expansible member, as and for the purpose specified. 90

3. A smoke plug comprising an expansible member fitted with an extending shank, a pipe extending at an angle from the shank and having the inner end thereof demountably associated with the shank, an adjusting bolt carried by the outer end of the pipe and fitted with a washer and an adjusting nut bearing on the latter end of the pipe and a cable connecting the bolt with the expansible member and passing through the 100 pipe and shank, as and for the purpose specified. 95

4. A smoke plug comprising an expansible member, a cable connected with the expansible member and demountable means 105 associated with the expansible member and the cable for adjusting the tension in the cable and effecting the expansion of the expansible member, as and for the purpose specified. 110

5. A smoke plug comprising an expansible member fitted with an open centered extending shank, a pipe disposed at an angle to the shank and having the inner end thereof demountably associated with the shank, 115 an adjusting bolt located at the outer end of the pipe and extending within the same, an adjusting nut on the bolt and engageable with the pipe end and a cable having one end secured to the inner end of the bolt and 120 the other end connected with the expansible member, said cable passing through the open centers of the shank and pipe, as and for the purpose specified.

6. A smoke plug comprising an expansible member fitted with an extending open centered shank, a hollow pipe disposed at an angle to the shank and having the inner end

thereof socketed in the shank, an adjusting bolt extending within the outer end of the pipe and fitted with an adjusting nut engageable with the latter end of said pipe, 5 means preventing the turning of the bolt in the pipe and a cable connecting the inner end of the bolt with the expansible member, said cable passing through the open center of the pipe and shank, as and for the purpose specified.

7. A smoke plug comprising an expansible member fitted with an extending open centered shank, a pipe having a hollow square center and the inner end thereof 15 socketed in the shank, an adjusting bolt located in the outer end of the pipe, and having the inner end thereof squared to fit the square center of the pipe, an adjusting nut on the bolt, said nut normally engaging the 20 adjoining end of the pipe, a roller located in the shank at the juncture of the shank and pipe and a cable connecting the inner end of the bolt with the expansible member, said cable passing through the open centers 25 of the pipe and shank and around the roller, as and for the purpose specified.

8. A smoke plug comprising a shank fitted with an open center and carrying a lower

face plate supplied on the upper side with a projecting rib, an upper face plate disposed above the latter face plate and provided with an extending spindle slidably received within the open center of the shank and with a projecting rib, a rubber band inserted between the face plates and surrounding the ribs, a pipe having a hollow square center disposed at an angle to the shank and having the inner end thereof socketed in the shank, an adjusting bolt located at the outer end of the pipe and having the inner end squared to fit the interior opening in the pipe, an adjusting nut mounted on the bolt and engaging normally with the outer end of the pipe, a roller contained in the shank immediately adjoining the juncture of the shank with the pipe and a cable connecting the inner end of the bolt with the spindle, said cable passing around the roller, as and for the purpose specified.

Signed at Winnipeg this 14th day of May 50
1914.
